UNITED STATES PATENT OFFICE

2,126,696

HEATER

Albert H. Bates, Rockford, Ill., assignor to Liberty Foundries Company, Rockford, Ill., a corporation of Illinois

Application June 27, 1935, Serial No. 28,606

6 Claims. (Cl. 257—137)

This invention relates to a hot water heater especially adapted for use on motor cars, utilizing the hot water from the engine cooling system and having a forced draft of air therethrough secured by means of an electric motor driven fan.

Heaters of the kind mentioned have been mounted on the dash in accordance with my Patent 1,834,674, utilizing the water pipes as supports for the radiator of the heater. The motor 10 for driving the fan was placed between the dash and the radiator, usually supported also from the water pipes. However, that arrangement is not satisfactory in certain makes of cars where the dash is so close to the front seats that there would 15 not be enough leg room left in front of the heater for comfort. Then, too, that arrangement made it unhandy to remove the motor for inspection and repair or replacement. It is accordingly the principal object of my invention to provide a 20 heater having the motor mounted on the opposite side of the dash, that is, in the engine compartment, whereby to permit placing the radiator of the heater closer to the dash than would otherwise be possible, and at the same time make the 25 motor easily accessible for removal and replacement, without disturbing the rest of the heater in any way.

In accordance with my invention, a tubular support rigid with the radiator extends through a 30 hole in the dash and a shaft mounted therein in a self-aligning bearing carries the fan on one end and a coupling having quickly detachable connection with the armature shaft of the motor on the other end, the motor being constructed so 35 that its bell housing has a telescoping fit on the end of the tubular support and may be fastened thereto detachably with a set screw to permit quick and easy mounting and dismounting of the motor.

40 The invention is illustrated in the accompanying drawing, in which—

Figure 1 is a section through the dash showing in side elevation a heater made in accordance with my invention mounted thereon;

45 Fig. 2 is a longitudinal section through the tubular support on a larger scale, and

Fig. 3 is a view similar to Figure 1 showing a modified or alternative construction.

Similar reference numerals are applied to corresponding parts throughout the views.

The heater shown in Figure 1 comprises an air heating radiator 4 supported by hot water supply and return pipes 5 and 6 on the dash 7 of an automobile. The fan 8, driven by the electric 55 motor 9, is disposed in the open back portion of

the sheet metal shroud 10 which encloses the back and sides of the core of the radiator 4. The fan draws air into the space between the radiator 4 and dash 7 and forces it through the radiator so as to induce circulation of warm air in the car in 5 the well known way. The pipes 5 and 6 are shown provided with nuts 11 and 12 threading thereon against opposite sides of the dash 7, whereby to clamp the heater firmly to the dash, the one nut of each pair acting as a lock nut for the other. 10

In accordance with my invention, the motor 9 instead of being mounted between the radiator 4 and dash 7, as in my patent previously mentioned, is carried on a tubular support 13 rigidly mounted on the radiator on arms 14 and projecting through a hole 15 in the dash, whereby to have the motor disposed on the opposite side of the dash in the engine compartment under the hood, thus enabling the mounting of the radiator 4 in closer proximity to the dash, as shown, and accordingly leaving more leg room for the front seat passengers. In certain cars, this construction enables the use of this type of heater, whereas, the old construction, due to the extent of its projection from the dash, could not be used. This construction, furthermore, locates the motor where it is easily accessible for removal and replacement. A washer 16 surrounding the tube 13 and held in place against the inside of the dash 7 by the arms 14 seals the hole 15. The arms 14 20 are suitably welded to the tube 13, as at 17, and have their outer ends flattened, as at 18, and suitably spot-welded to the shroud 10. 25

Referring to Fig. 2, it will be seen that the tube 13 houses a shaft 19 which has the hub 20 30 of the fan 8 suitably secured to the projecting end thereof. A coupling 21 on the other end of the shaft provides a detachable driving connection between the shaft 19 and the armature shaft 22 of the motor 9. The coupling 21 is preferably 35 of molded rubber of tubular form with a transverse partition wall 23 at the middle. The tubular ends must be spread to receive the ends of the shafts 19 and 22 and in that way a good frictional driving connection is secured, the wall 23 serving 40 by abutment with the end of either shaft in assembling to insure approximately the same length of connection with both shafts. The wall 23 is stretched in the expansion of the tubular ends of the coupling and accordingly makes for 45 a tighter hold of the coupling on both shafts. This wall also reinforces the coupling where the greatest strain is concentrated in the driving 50 of the fan, thus making for durability. The flexibility of the coupling also compensates for 55

whatever slight misalignment there may be between the shafts 19 and 22. However, the shaft 19 is mounted in a self-aligning bearing 24 adjacent the fan 8 in the end of the tube 13 remote from the motor 9, whereby to insure proper alignment between the shafts 19 and 22 when coupled. The bearing 24 is in the form of a ball having parallel flats machined thereon and a bearing hole 25 drilled therethrough to accommodate the shaft 19. The tube 13 is counter-bored adjacent the bearing 24, as at 26, to provide an annular shoulder 27 in longitudinally spaced relation to the bearing serving as a seat for a coiled compression spring 28. A felt washer 29 is held in engagement with the spheroidal surface of the bearing 24 by a metal washer 30 under the action of the spring 28. Another felt washer 31 engages the bearing 24 from the opposite side and is retained by a washer 32 which, in turn, is retained in the end of the tube 13 by the inwardly spun end 33 of the tube. The motor 9 has a bell housing 34, the hub 35 of which has a telescoping fit with the other end of the tube 13. A set screw 36 in the hub 35 serves to fasten the motor securely and yet permit of quick and easy removal when desired. In the mounting of the motor, the shaft 19 is held against endwise movement in the tube 13 by a washer 37 which comes into abutment with the washer 30 and is held in place by a split ring 38 that snaps into an annular groove 39 provided in the shaft 19.

It should be evident from the foregoing description that smooth and quiet operation of the fan is insured even though the motor is in remote relation thereto and has a detachable driving connection therewith, as described. There is no danger of vibration and consequent noise, owing to the fact that the shaft 19 has both a self-aligning bearing 24 and a resilient flexible coupling 21. Whenever the motor requires any attention as, for example, replacement of brushes, the set screw 36 is simply loosened and the motor can then be removed, and later as easily replaced, without disturbing the rest of the heater in any way.

In Fig. 3, I have shown another heater, the radiator 4 of which is supported on a tube 13' clamped to the dash 1, as at 40. The tube 13' has arms 14' extending therefrom and secured to the shroud 10 of the radiator for support of the latter. In other words, the radiator does not rely for its support upon the water pipes, as in the other heater. For that reason, the hoses 41 and 42 for supply and return of the hot water 55 are simply extended through holes in the dash and attached to the inlet and outlet nipples 43 and 44 of the heater, as by clamps 45. The fan 8 will, of course, be driven by the motor 9 in the same manner previously described.

It is believed the foregoing description conveys a good understanding of the objects and advantages of my invention. The appended claims have been drawn with a view to covering all legitimate modifications and adaptations.

I claim:

1. In a heater comprising a radiator adapted to be supported in spaced relation to the dash of an automobile or other vehicle, a fan between the dash and the radiator for causing a forced draft of air through the latter to be heated thereby, and a motor comprising an armature shaft for driving the fan, said motor adapted to be supported on the other side of said dash, a combined radiator, motor, and fan support comprising a tubular member extending through an

opening provided in the dash and having said radiator rigidly supported on one end portion thereof and said motor demountably supported on the other end portion on the opposite side of the dash from the radiator, fastening means for securing said tubular member to the dash by its intermediate portion, and a shaft extending through the tubular member and providing a detachable driving connection between the fan and the armature shaft of the motor. 5

2. In a heater comprising a radiator adapted to be supported in spaced relation to the dash of an automobile or other vehicle, a fan between the dash and the radiator for causing a forced draft of air through the latter to be heated thereby, and a motor comprising an armature shaft for driving the fan, said motor adapted to be supported on the other side of said dash, a combined radiator, motor, and fan support comprising a tubular member extending through an opening provided in the dash and having said radiator rigidly supported on one end portion thereof and said motor demountably supported on the other end portion on the opposite side of the dash from the radiator, fastening means for securing said tubular member to the dash by its intermediate portion, a shaft fixed to said fan and supported in a tiltable bearing in said tubular member, the shaft extending in said member toward the motor, and means providing a flexible 20 detachable driving connection between the fan shaft and the armature shaft of the motor. 25

3. In a universally self-aligning rotary shaft bearing structure of the character described, the combination of a rotary shaft adapted to be suitably driven at one end and to carry a driven member on the other end, a tubular member suitably supported having a bore large in diameter relative to said shaft, a bearing block of spheroidal form having an axial hole wherein the intermediate 40 portion of the shaft is rotatably mounted, washers having a sliding fit within the tubular member and providing opposed bearings for the spheroidal bearing block in fore and aft spaced relation, retaining means cooperating with the outer washer 45 to prevent endwise displacement of the bearing block and washer assembly outwardly relative to the tubular member, and spring means yieldingly urging the inner washer outwardly whereby to maintain substantially uniform bearing pressure 50 on the bearing block while permitting tilting movement thereof and corresponding tilting movement of the shaft.

4. A structure as set forth in claim 3, wherein the inner washer has an inturned annular flange 55 providing a substantially flat annular bearing surface on the back thereof, the structure including a washer mounted on the shaft and held against endwise movement relative thereto and adapted to engage said bearing surface to limit 60 endwise movement of said shaft outwardly relative to the tubular member.

5. A structure as set forth in claim 3, wherein the tubular member has that portion of the bore thereof, wherein the bearing block and washers 65 are mounted enlarged with relation to the rest of the bore, whereby an annular shoulder is defined at the inner end of said enlarged bore, and wherein the spring means urging the inner washer outwardly comprises a coiled compression spring fitting freely in the enlarged bore and engaging the annular shoulder at one end and the inner washer at the other end. 70

6. A structure as set forth in claim 3, wherein the tubular member has that portion of the bore 75

thereof, wherein the bearing block and washers are mounted enlarged with relation to the rest of the bore, whereby an annular shoulder is defined at the inner end of said enlarged bore, and where-
5 in the spring means urging the inner washer outwardly comprises a coiled compression spring, fitting freely in the enlarged bore and engaging the annular shoulder at one end and the inner

washer at the other end, said structure further including a washer mounted on said shaft and held against endwise movement relative thereto and arranged to engage a portion of the inner washer to limit endwise movement of the shaft 5 outwardly relative to the tubular member.
